CLAIM

The ornamental design for a rope untangling game, as shown and described.

DESCRIPTION

FIG. 1 is a first perspective view of a rope untangling game showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of another state of the rope untangling game thereof;

FIG. 10 is an enlarged view of the selected portion 10 in FIG. 1; and,

FIG. 11 is an enlarged view of the selected portion 11 in FIG. 2.

The dash-dash broken lines shown in the drawings depict portions of the rope untangling game that form no part of the claimed design. The dot-dash broken lines in FIGS. 1, 2, 10 and 11 illustrate the periphery of the enlarged views of the rope untangling game and form no part of the claimed design.
